UNITED STATES PATENT OFFICE.

ARTHUR BATES AND ALFRED EDWARD RICHARDS, OF LEICESTER, ENGLAND, AS-SIGNORS TO UNITED SHOE MACHINERY COMPANY, OF PATERSON, NEW JERSEY, A CORPORATION OF NEW JERSEY.

SEWING-MACHINE.

1,188,389.

Specification of Letters Patent. Patented June 27, 1916.

Application filed February 13, 1913. Serial No. 748,148.

To all whom it may concern:

Be it known that we, ARTHUR BATES and ALFRED EDWARD RICHARDS, subjects of the King of England, residing at Leicester, Leicestershire, England, have invented certain Improvements in Sewing-Machines, of which the following description, in connection with the accompanying drawings, is a specification, like reference characters on 10 the drawings indicating like parts in the several figures.

This invention relates to machines used in the manufacture of boots and shoes and more particularly to that type of machine 15 in which a curved needle is provided to effect the permanent stitching together of the sole and upper of turn shoes. An example of a sewing machine of this type is what is known in the trade as the Goodyear 20 welt and turn shoe sewing machine and the stitch-forming devices of this machine are applicable with particular advantage to machines constructed in accordance with the present invention.

25 The object of the present invention is the provision of a sewing machine of the above general type but which is so organized as to be capable of sewing an unlasted shoe upper permanently to a sole and which is 30 adapted to be of very advantageous use in connection with turn shoes having soles of flexible material (such as felt) that may be or may not be provided with channel lips.

35 Felt soled shoes as now made generally comprise a textile fabric upper and a felt sole, and these parts have been heretofore sewn together by hand without any preparatory lasting process, the handcraftsman lasting or manipulating the upper and 40 sole as he or she stitches them together so as to insure the correct relationship of the two parts. By the use of a machine constructed according to this invention shoes of this kind have their unlasted uppers and 45 soles, without the use of a last, manipulated into a correct relationship of their adjacent edges and permanently sewn together at a single operation. In the present machine there is provision for securing an unlasted shoe upper, *i. e.* an upper off the last, 50 permanently to a sole, the machine being characterized by a rotary or other horn adapted to support one face of successive

portions of the sole margin (the sole and upper being outside in, if the work be a 55 turn shoe) and a member that coöperates with the horn to hold the marginal portion of the upper against the other face of the sole and in such relationship to a preferably work-feeding or other curved needle 60 that the barbed point of the said needle will pierce through both the margin of the upper and that surface only of the sole that is adjacent thereto to permanently 65 stitch them together. The member coöperating with the horn may consist of a presser foot which may be so formed as to co-act with a corresponding part on the horn to cause a portion of the shoe bottom to be raised locally opposite the curved needle 70 so that the needle may penetrate both upper and sole without making too broad a seam. Conveniently, this presser foot may be of claw-like or bifurcated formation so as to engage the work at points displaced at each side of the point where the end of the horn engages it, and the said end of the horn may be formed or provided with a projection or button so that when the work is pressed between the presser foot 75 and the horn a ridge, mound or projection in the work will be produced through which the needle can enter and then emerge near the point of entrance.

In accordance with a feature of this invention the arrangement of the horn and its coöperating member or presser foot, in a machine having the above mentioned characteristics or their broad equivalents for the described or similar work, is such 80 that they are separated in a novel manner to permit the feed of the work. In the preferred construction the horn is operatively connected with the presser foot and so correlated that when the horn is depressed the presser foot is lifted. This arrangement provides that the work shall be freed more quickly and thoroughly for the purpose of feeding, and for enabling a more ready manipulation of the upper and sole 85 90 95 100 105 into correct relationship than is the case when the presser foot alone is moved.

In the machine hereinafter described the feed of the work is effected by the curved needle. This is accomplished by mounting the needle-carrying lever in a slide arranged

to have a horizontal motion imparted to it by appropriate mechanism, the connections for imparting the oscillatory movement to the needle being suitably arranged to permit 5 of this horizontal movement. With certain classes of work and particularly with shoes having flexible soles it is found that the feed of the work by the curved needle is accomplished with greater efficiency and at the 10 same time the machine is rendered simpler than it is with the usual feed devices and associated parts. When a curved needle is employed for the purpose of feeding the work as above set forth it is found that the 15 feature of a combined lift of the presser foot with a depression of the horn is of particular advantage. This is by reason of the needle after it has penetrated the work tending to bind the material against the work supports 20 thus rendering difficult the feeding of the work and this difficulty is efficiently overcome by the horn being dropped and the presser foot raised during such feeding movement.

25 With this purpose in view the invention also comprises the provision of operative connections between the needle, horn and presser foot so arranged that as the feed is effected by the needle the horn is lowered and the 30 presser foot lifted. But it is considered to be within the scope of the invention to employ such connections between the needle and either the horn or the presser foot.

As hereinbefore stated the presser foot 35 conveniently is bifurcated or claw-shaped; and it is so constructed that sufficient space is afforded between the limbs of the same to allow for the feeding movement of the curved needle. Conveniently, an edge gage 40 for the work is located between the said limbs, and the said gage may be adjustable so as to permit of variation in the distance from the edge at which the stitching takes place.

45 The machine is also provided with means for depressing the horn by a treadle to a greater extent than it is in the feed movement for the reception and removal of the work and conveniently a "lost motion" connection is provided between the horn and the presser foot to permit this extended movement to take place without raising the presser foot to a corresponding extent. The 50 lost motion connection may be yielding and 55 an adjustable stop may be provided to adjust the height to which the presser foot may be lifted.

These and other features of the invention will now be described as embodied in the 60 illustrated machine. It is to be understood, however, that this embodiment is by way of illustration merely and not by way of limitation, since the invention could be embodied in other forms and the construction, disposition and operation of the parts could be

varied without departing from the spirit thereof.

In the said drawings:—Figure 1 is a side view of the machine, with parts in section, of sufficient of the stitch-forming mechanism 70 of the well-known type of Goodyear sewing machine to enable the invention to be understood; Fig. 2 is a detail plan of the shoe-engaging devices; and Fig. 3 is an enlarged view of the parts closely adjacent to the shoe 75 and of the shoe in section.

In the illustrated construction the sewing machine comprises a head 2 that supports the usual stitch-forming devices including a curved needle 3 and a looper 4 located above 80 a curved horn 5 upon which the work is supported for the sewing operation.

The horn is shaped to enter a shoe and is mounted, preferably so as to be capable of rotation, to bring different parts of the shoe 85 into operative relationship with the sewing devices. Further the horn is adapted to be depressed by connection with a treadle for the reception and removal of work and, as will appear later herein, is automatically depressed to a lesser extent to enable the work 90 to be fed. To this end the horn 5 is provided with a sleeve 6 that is received within a bore in a bracket 7 projecting from the base of the head 2 and surrounds a supporting spindle 8 upon which it is capable of being rotated, for which purpose a ball bearing 9 is provided between the lower end of the sleeve 6 and an enlargement 10 of the spindle 8. Relative vertical movement be-

tween the spindle and the sleeve is prevented by the boss 11 of an arm 12 fixed to the spindle 8 by a bolt 13, this boss engaging in a recess in the upper end of the sleeve. The sleeve 6 is of sufficient length to permit of an 100 up and down motion in the bracket 7 and is raised and lowered by a toggle 14, 15 the upper end of the link 14 being connected with the spindle 8 at 16 while the lower link 15 is centered at 17 in the bracket 7 and is in 105 the form of a bell-crank lever the outwardly extending arm 18 of which is connected with a treadle rod 20. A screw 21 threaded through the frame forms an abutment for the central joint of the toggle and acts as an 110 adjustable stop to regulate the height to which the horn will be raised, this raising being accomplished by a spring 19 that connects the arm 18 of the bell-crank lever with the frame and tends to maintain the toggle 115 straightened. The screw 21 is provided with a lock nut 22 to maintain it in the position to which it has been adjusted.

From the foregoing it will be understood that the curved horn 5 is normally held in 120 raised position, which is variable according to circumstances, by the spring 19 but that it can be lowered for the removal, insertion or manipulation of the work by the "breaking" of the toggle by lowering the rod 20 125

through the operation of a treadle to which the rod is connected.

The horn is curved as aforesaid so as to extend within the shoe and is provided at 5 its upper end with a projecting button 25 that forms a support for the shoe sole. In the present construction the button is circular in plan and its upper surface is of spherical convex formation so as to raise a 10 portion of the shoe bottom into a mound.

Coöperating with the projecting button 25 is a presser foot or clamping device 26 which is bifurcated, as shown in Fig. 2, to form fingers 27, 28, arched in a vertical 15 plane, and which, by engaging the work serve to press the upper and sole together and to deform the sole so as to provide a projection through which the curved needle 3 can penetrate. The claw 27 under 20 which the work first passes preferably is beveled in order to avoid marring the work and also to assist the passing of the work under it when manipulated by the operator; and it may, if desired, be shorter than its 25 companion 28.

The presser foot 26 is pivoted at 29 to the upstanding ears 30 of a bracket 31 (see Fig. 2) secured to a projecting portion 32 of the head 2. An edge gage 33 for positioning the work is provided, and the flat shank portion 34 of this gage extends under the bracket 31, being adjustably secured thereto by a thumb-screw 35 which passes through a slot in the portion 34 and 35 screws into the said bracket. Extending under the presser foot is an enlargement 36 formed on the front of the shank portion 34 of the gage, this enlargement serving as a means for determining the distance 40 between the line of stitches and the edge of the work and also assisting in positioning the upper in the desired relation to the sole immediately before the upper is secured thereto. That side of the enlargement 36 which first engages the work, *i. e.*, the right-hand side as viewed by the operator, is formed with an upstanding lip 37 that abuts against the leading side of the presser foot, while another projection 45 38 extends upward between the fingers 27, 28, as shown in Fig. 2.

It is to be understood that in the use of the machine constructed according to this invention for the manufacture of felt soled 55 turn shoes the edge of the upper overlaps the edge of the sole and in this position they are presented to the machine to be sewn and are afterward turned inside out. In this embodiment of the invention the 60 work is fed by the needle 40 which is of the curved type that in penetrating moves in the arc of a circle. For thus feeding the work the needle carrying lever 42 is mounted on a bracket 43 depending from a slider 65 44 that is adapted to be moved horizontally

toward the left-hand side of the machine after the needle has penetrated the work to feed the work, suitable mechanism being provided to accomplish this movement. To allow the feeding movement of the work 70 by the needle the horn is lowered and this is effected by connections between the needle-actuating mechanism and the horn-lowering device. These connections may comprise a link 45 connected at one end to 75 the lever 46 by which the needle is oscillated through its arc and at the other end to an arm 47 loosely mounted at 17 on the stud or spindle on which is mounted the bell-crank lever forming the lower element 80 15 of the toggle. The lever 46 is pivoted at 48 to the machine frame and carries a cam roll 49 that stands in a groove cut in the side of a cam disk mounted on the main shaft. The movements thus imparted to the 85 lever 46 are communicated to the needle by a link 50 universally jointed at one end to the needle-carrying lever 42 and at the other end to the lever 46. The universal joints permit the lateral movement of the 90 needle to feed the work. The arm 47 has adjustably secured to it, by a screw and slot connection, a plate 51 having a laterally projecting tappet 52 which operates on an extension 53 of the arm 18 of the bell-crank 95 lever 15, 18 and sufficient "lost motion" is provided between the contacting surfaces to provide a lowering of the horn merely sufficient to enable the work to be fed freely. The adjustment of the plate 51 on the arm 100 47 enables the operator to vary at will the extent to which the horn is lowered during the feeding movement. To prevent the treadle rod from being moved while the horn is automatically lowered for the feeding of the work the connection between the treadle rod 20 and the arm 18 of the bell-crank lever is constituted by a pin 54 projecting from the latter that enters a slot 55 in the treadle rod which is normally 105 maintained raised by a spring 56 that connects it with a projection upon the frame. A stud 57 carried by the treadle rod 20 limits its upward movement by contacting with the said projection. In this embodiment of the invention in addition to the horn being lowered the presser foot is raised while the work is fed by the needle and consequently connections are provided 110 between the presser foot and the horn-lowering device. These connections are arranged as follows:—The afore-mentioned arm 12 that is secured at one end to the upper end of the spindle 8 rigidly supports at its other end an upright stud 58. On this 115 stud two collars 59, 60 are pinned at a distance apart, so as to leave a space between them in which is located a block 61 that slides on the stud 58 and that is normally kept in contact with the lower collar 120 125 65. On this block 61 is secured a link 66 that is pinned to the treadle rod 20 and that is normally kept in contact with the lower collar 130.

60 by a spring 62 which is disposed between the block 61 and the upper collar 59. The block 61 is connected by a link 63 with the rear end of the presser foot 26.

5 An abutment 65 on the bracket 31 is provided below the rear arm of the presser lever so that when the presser is raised from the work for the purpose of feeding the rear arm will rest on the abutment and the 10 presser foot will be held stationary clear of the sewing devices, the spring 62 providing for the further downward movement of the horn after the presser foot has been raised.

Any suitable device may be provided to 15 enable the height to which the presser foot is lifted to be varied, such for example as a screw threaded through the rear arm of the presser foot and adapted to engage the abutment 65.

20 The operation of the machine as far as concerns the present invention no doubt will be understood from the foregoing description of the different parts but it may be briefly recapitulated as follows:—The operator 25 depresses the treadle and thereby through the treadle rod 20 and connected bell-crank lever "breaks" the toggle and lowers the horn ready for the reception of the work. After this has been placed upon 30 the horn the treadle is released, the toggle is straightened and the work pressed between the end of the horn and the claw-like end of the presser foot 26, which latter has been depressed through the arm 12, link 63 and 35 other parts connecting the presser foot with the horn. The machine is then started and during the progress of the stitching the work is fed by the transverse movement of the needle, the horn being lowered automatically and the presser foot raised at each 40 stitch through the loosely mounted arm 47 and tappet 52 that comprises part of the connections between the needle-actuating lever 46 and the horn-lowering device.

45 Having thus described our invention, what we claim as new and desire to secure by Letters Patent of the United States is:—

1. A machine for securing an unlasted shoe upper permanently to a sole off the last 50 having, in combination, a curved needle and operating mechanism therefor, a horn adapted to extend within the shoe and support successive portions of the sole margin and a member that co-operates with the 55 horn to clamp the marginal portion of the upper against the outer face of the sole and in such relationship to the curved needle that the barbed point of the said needle will pierce through both the margin of the upper 60 and that surface only of the sole that is adjacent thereto to permanently stitch them together, and means by which the horn is lowered and the said clamping member also lifted automatically to permit the feed of 65 the work.

2. In a machine for permanently sewing together an unlasted shoe upper and its sole, a needle and its operating mechanism, a horn, a clamping foot co-operating therewith to hold the marginal portion of the upper 70 against the top face of the sole for the needle to pierce through both the margin of the upper and that surface only of the sole that is adjacent thereto, means by which the horn is lowered automatically to permit the feed of the work, and connections from the horn to the clamping foot by which the foot is raised when the horn is lowered.

3. In a machine for permanently sewing together an unlasted shoe upper and its sole, 80 a needle and its operating mechanism, a horn, a clamping foot co-operating therewith to hold the marginal portion of the upper against the top face of the sole for the needle to pierce through both the margin of the upper and that surface only of the sole that is adjacent thereto, means by which the horn is lowered automatically to permit the feed of the work, and connections from the horn to the clamping foot by which the foot 85 may be raised a limited distance as the horn is lowered and thereafter the horn may be 90 lowered separately.

4. In a machine for permanently sewing together an unlasted shoe upper and its sole, 95 a needle and its operating mechanism, a horn, a clamping foot co-operating therewith to hold the marginal portion of the upper against the top face of the sole for the needle to pierce through both the margin of the upper and that surface only of the sole that is adjacent thereto, and connections from the needle operating mechanism to the horn by which the horn is depressed for permitting the feed of the work.

5. In a machine of the class described, the combination with a curved needle and its operating mechanism including means to actuate the needle to feed the work, of a clamping foot and a horn and connections by which the clamping foot is raised and also the horn is depressed while the needle is feeding the work to prevent the curved needle from binding the material on either 100 said foot or horn while feeding.

6. In a machine of the class described, the combination with a curved needle and its operating mechanism including means to actuate the needle to feed the work, of a clamping foot and connections from the needle actuating mechanism to the clamping foot by which the foot is raised by the needle actuating mechanism while the needle is feeding the work.

7. In an apparatus for permanently sewing together a shoe upper and its sole, a curved needle and its operating mechanism and associated stitch forming and setting parts, combined with a rotary horn arranged to engage the inner side of the sole 125 130 135

- and support the work relatively to the path of the curved needle for the sewing operation through the margin of the upper and into and out of the upper face of the sole, 5 means to actuate the stitch forming mechanism to effect the feeding of the work, and automatic means to lower and raise the horn in timed relation with the feeding movements.
- 10 8. In an apparatus for permanently sewing together a shoe upper and its sole, a curved needle and its operating mechanism and associated stitch forming and setting parts, combined with a rotary horn arranged to engage the inner side of the sole and support the work relatively to the path of the curved needle for the sewing operation through the margin of the upper and into and out of the upper face of the sole, 15 means to press the work down upon the horn, and automatic means for depressing the horn and also raising the presser in timed relation with the stitch forming operations to permit work feeding movements.
- 20 9. In a machine of the class described, the combination with a needle and its operating mechanism and associated parts for forming and setting stitches and feeding the work, of a horn for supporting the sole and 25 upper in position for the needle to operate upon them, a connection from the stitch forming mechanism to the horn to depress automatically the horn to permit feeding of the work, and a treadle mechanism for depressing the horn to permit insertion of the work, a lost motion connection being formed 30 between the horn and the automatic depress- ing mechanism to permit depressions of the horn.
10. In a machine of the class described, 40 the combination with suitable operating mechanism of a work feeding needle, a horn, a presser foot and operative connections between the needle, horn and presser foot so arranged that as the feed is effected by the 45 needle the horn is lowered and the presser foot is lifted.
11. In a machine of the class described, 50 the combination with suitable operating mechanism of a needle, a horn, a presser foot, actuating mechanism to effect feeding of the work, and operative connections between the said actuating mechanism, needle, horn and presser foot so arranged that as the feed takes place the horn is lowered and 55 presser foot is lifted.
12. In a machine of the class described, 60 the combination with suitable operating mechanism of a work feeding needle, work holding members including a horn and a 65 presser foot and operative connections between the needle and one of said work holding members so arranged that prior to the needle feed the work is unclamped and held unclamped by the needle operating mechanism during the feed.
- In testimony whereof we have signed our names to this specification in the presence of two subscribing witnesses.
